COMBINED HOOK, PAD, AND PENCIL HOLDER ATTACHMENT FOR A WALL TELEPHONE

Rudolph E. Brau and Annie M. Brau, both of 3002 26th Ave., Kenosha, Wis.

Filed June 16, 1961, Ser. No. 65,621

Term of patent 14 years

(Cl. D26—14)

The broken line showing of a well type telephone and pencil in FIGURES 2 and 3 is for illustrative purposes only.

We claim:

The ornamental design for a combined hook, pad, and pencil holder attachment for a wall telephone, as shown and described.
